(57) **CLAIM**

The ornamental design for a portable heated water system, as shown and described.

DESCRIPTION

FIG. 1 is a top front perspective view of our new design for a portable heated water system;

FIG. 2 is a bottom back perspective view thereof;

FIG. 3 is a left elevation view thereof;

FIG. 4 is a right elevation view thereof;

FIG. 5 is a front elevation view thereof;

FIG. 6 is a back elevation view thereof;

FIG. 7 is a top plan view thereof; and,

FIG. 8 is a bottom view thereof.

The broken lines shown represent features of the portable heated water system that form no part of the claimed design.
